UNITED STATES PATENT OFFICE

2,499,757

SPACE HEATING APPARATUS

Huey M. Jordan, Nemacolin, Pa.

Application August 17, 1948, Serial No. 44,669

1 Claim. (Cl. 237—1)

1

This invention relates to new and useful improvements and structural refinements in a space heating apparatus and the principal object of the invention is to facilitate heating of space by heat generated during the compression of a gas, such as air, thus eliminating the conventionally employed burners and other combustion devices.

This object is achieved by the provision of a space heating apparatus which embodies in its construction a motor driven gas compressor, a reservoir and a plurality of heat distributors, the heat generated in the gas compressed by the compressor being distributed by the heat radiators throughout the space which is to be heated. The invention is particularly adapted for use for heating homes, offices, and the like, and important advantages of the invention reside in its simplicity of construction and in its adaptability for efficient, continuous service with the minimum amount of attention.

With the above more important objects and features in view and such other objects and features as may be apparent as this specification proceeds, the invention consists essentially in the arrangement and construction of parts as illustrated in the accompanying drawings, in which:

The figure in the drawing is a cross sectional view of a building showing the heating apparatus installed therein.

Referring now to the accompanying drawings in detail, the reference character 10 designates a building including a basement 12 and a plurality of rooms 14, 16 which are to be heated, the heating apparatus being designated generally by the reference character 18.

The heating apparatus 18 embodies in its construction a compressed air tank 20, preferably housed in the basement 12 and providing what may be referred to as a base for an air compressor 22 driven by an electric motor 24 through the medium of a belt drive 26.

The compressor 22 is provided with an inlet pipe 28 which, in turn, is connected by means of a T 30 to a duct 32 communicating with the tank 20, while a further duct 34 extends from the T 30 and carries an air cleaner 36 communicating with the atmosphere. An inlet shut-off valve 38 is provided in the duct 34 between the air cleaner 36 and the T 30, while a circulation shut-off valve 40 is provided in the duct 32 between the T 30 and the compressor 20, as will be clearly apparent.

Suitable heat radiators 42, 44 are installed

2

in the various rooms 14, 16, these radiators being connected together in series, as indicated at 46, and also being connected in series to the compressed air tank 20 and to the air compressor

5 22 as indicated at 48, 50, respectively.

The conduit 50, of course, communicates with the exhaust of the air compressor 22, and when the invention is placed in use, the air inlet valve 38 is opened while the circulation valve 40 is closed, so that when the compressor is energized by the motor 24, substantial air pressure will be built up in the conduits 50, 46, 48, in the radiators 42, 44 and in the tank 20.

Thereupon, the valve 38 is closed and the valve 15 40 is opened, so that complete, uni-directional circulation of compressed air from the compressor 22 is established through the conduits 50, 46, 48 and through the radiators 44, 42, to the tank 20 and then to the air compressor.

20 In this manner, the heat generated in the compressed gas (air) will pass through the radiators 42, 44 and will be distributed thereby into the space (14, 16) which is to be heated, as will be clearly apparent.

25 If desired, a suitable thermostat 52 may be installed in one or more of the rooms 14, 16, this thermostat being electrically connected, as at 54, to the motor 24 so that the motor becomes energized and ceases to be energized automatically in response to the rise and fall of temperature

30 in the various rooms.

Moreover, the radiators 42, 44 may be provided with a by-pass illustrated at 56 in association with the radiator 42, the by-pass being 35 equipped with a shut-off valve 58 while additional shut-off valves 60, 62 are provided in the supply and delivery conduits immediately adjacent the radiator, so that by simply opening the valve 58 and closing the valves 60, 62, the heated air may be diverted through the by-pass 56 without heating the room 14. Alternatively, by closing the valve 58 and opening the valves 60, 62, the heated air will pass through the radiator 42 rather than through the by-pass, as will be clearly apparent.

45 It is believed that the advantages and use of the invention will be clearly understood from the foregoing disclosure, and accordingly, further description thereof at this point is deemed 50 unnecessary.

Having described the invention, what is claimed as new is:

In a space heating apparatus, the combination of a motor driven gas compressor including an inlet port and an outlet port, a compressed

gas reservoir having an inlet port and an outlet port, a heat radiator, a delivery conduit extending from the outlet port of said compressor to said radiator, a return conduit extending from the radiator to the inlet port of said reservoir, a pipe extending outwardly from the inlet port of the compressor, a T-coupling having one arm thereof mounted on the outer end of said pipe, a tube connecting the outlet port of the reservoir to another arm of said coupling, a shut-off valve on said tube, and a second shut-off valve provided on the remaining arm of the coupling and adapted to communicate with the atmosphere, whereby air may be admitted to said compressor

selectively from said tank and from the atmosphere through the medium of said valves.
